CLAIM

The ornamental design for a cryogenic vial, as shown and described.

DESCRIPTION

FIG. 1 is a front, right side, top perspective view of a first embodiment of a cryogenic vial showing our new design; FIG. 2 is a rear, left side, bottom perspective view of the cryogenic vial illustrated in FIG. 1;

FIG. 3 is a front elevation view of the cryogenic vial illustrated in FIG. 1;

FIG. 4 is a right side elevation view of the cryogenic vial illustrated in FIG. 1;

FIG. 5 is a left side elevation view of the cryogenic vial illustrated in FIG. 1;

FIG. 6 is a rear elevation view of the cryogenic vial illustrated in FIG. 1;

FIG. 7 is a top plan view of the cryogenic vial illustrated in FIG. 1;

FIG. 8 is a bottom plan view of the cryogenic vial illustrated in FIG. 1;

FIG. 9 is a front, right side, top perspective view of a second embodiment of a cryogenic vial showing our new design; FIG. 10 is a rear, left side, bottom perspective view of the cryogenic vial illustrated in FIG. 9;

FIG. 11 is a front elevation view of the cryogenic vial illustrated in FIG. 9;

FIG. 12 is a right side elevation view of the cryogenic vial illustrated in FIG. 9;

FIG. 13 is a left side elevation view of the cryogenic vial illustrated in FIG. 9;

FIG. 14 is a rear elevation view of the cryogenic vial illustrated in FIG. 9;

FIG. 15 is a top plan view of the cryogenic vial illustrated in FIG. 9; and,

FIG. 16 is a bottom plan view of the cryogenic vial illustrated in FIG. 9.

The dashed lines in the drawings depict portions of the cryogenic vial that form no part of the claimed design.
